HAT

Milton A. Dannenberg, Chicago, Ill., assignor to
Silberman Fur Corporation, Chicago, Ill., a corporation of Illinois

Application May 12, 1951, Serial No. 15,151

Term of patent 14 years

(Cl. D3—13)

To all whom it may concern:

Be it known that I, Milton A. Dannenberg, a citizen of the United States, residing at Chicago, in the county of Cook and State of Illinois, have invented a new, original, and ornamental Design for a Hat, of which the following is a specification; reference being had to the accompanying drawing, forming a part hereof.

In the drawing:

Fig. 1 is a side perspective view of a hat, showing my new design;

Fig. 2 is a top plan view; and

Fig. 3 is a front elevational view thereof.

My design for a hat is characterized by the centrally disposed fur trim extending from front to rear across the flat top panel and merging with the upper end of the tail, in relation to and in association with the remaining portions all as shown.

I claim:

The ornamental design for a hat, substantially as shown and described.

MILTON A. DANNENBERG.
